J. J. FISCHER

ADJUSTABLE COMBINATION WINDOW SHADE AND CURTAIN POLE HOLDER

Filed Feb. 17, 1925

UNITED STATES PATENT OFFICE.

JOHN J. FISCHER, OF ARCADIA, INDIANA, ASSIGNOR OF FORTY-NINE ONE-HUNDREDTHIRTY-THREE TO NOEL WHISLER, OF ARCADIA, INDIANA.

ADJUSTABLE COMBINATION WINDOW-SHADE AND CURTAIN-POLE HOLDER.

Application filed February 17, 1925. Serial No. 9,813.

To all whom it may concern:

Be it known that I, JOHN J. FISCHER, a citizen of the United States, residing at Arcadia, in the county of Hamilton and 5 State of Indiana, have invented certain new and useful Improvements in Adjustable Combination Window-Shade and Curtain-Pole Holders; and I do hereby declare the following to be a full, clear, and exact description of the invention, such as will enable others skilled in the art to which it appertains to make and use the same.

This invention relates to combined window shade brackets and curtain pole supports, and more particularly to devices of 15 this character which are adjustable to accommodate shade rollers of different lengths.

The invention has for one of its objects the provision of a combined window shade 20 bracket and curtain pole support of the character stated which shall be adapted to be secured to a window, door frame or other frame without the use of nails or screws, whereby to prevent the marring of the wood-work and permit the application of the 25 device in a comparatively short time and with an expenditure of comparatively little effort.

A further object of the invention is the provision of a combined window shade 30 bracket and curtain pole support of the character stated which shall be neat in appearance, which shall comprise comparatively few parts, and which can be manufactured at a comparatively low cost.

With the above and other objects in view, 35 the invention consists of the construction, combination and arrangement of parts hereinafter fully described and claimed, and illustrated in the accompanying drawing, 40 wherein:

Figure 1 is a view in front elevation of the upper portion of a window frame illustrating the application of the combined shade bracket and curtain pole support,

Figure 2 is a sectional view taken on the vertical plane indicated by the line 2—2 of Figure 1, looking in the direction indicated by the arrows,

Figure 3 is a sectional view taken on the 50 horizontal plane indicated by the line 3—3 of Figure 1, looking in the direction indicated by the arrows, and

Figure 4 is a detail view in rear elevation of the attaching and supporting plate of the

combined window shade bracket and curtain 55 pole support.

Corresponding and like parts are referred to in the following description, and designated in the accompanying drawing, by similar reference characters.

In the drawing, 1 designates the side and 2 the top of a window casing which is shown for the purpose of illustrating one application of the combined window shade bracket and curtain pole support.

The device comprises a plate 3 which is preferably of elongated rectangular formation and which is adapted to be secured to a door, window or other frame by prongs 4. These elements are secured to the ends 70 of the plate 3 by spring arms 5 which tend to constantly urge the prongs 4 in the direction of each other, whereby to prevent the prongs from becoming accidentally withdrawn from the casing of the door, window 75 or other frame to which the device is applied. A spring tongue 6 preferably provided with curved side edges 7 and a substantially circular lower end 8, depends from the lower edge of the plate 3. A block 9 80 preferably made of rubber and adapted to assist the prongs 4 in supporting the plate 3, is secured to the inner side of the lower end 8 of the tongue 6, and is adapted to be held in frictional contact with the face of the frame by the tongue.

An angular arm 10 having a vertical member 11 and a horizontal and forwardly extending member 12, is connected to the plate 3 for longitudinal adjustment with respect thereto by means of a bolt 13 which passes 90 through a longitudinally extending slot 14 in the plate 3 and through the vertical member 11. By turning the nut 15 of the bolt 13 in one direction, the arm 10 is secured to the plate 3 against casual movement in the 95 direction of the length thereof, and by turning the nut in the reverse direction, the arm is freed for adjustment longitudinally of the plate. To prevent the arm 10 from having any rocking movement on the bolt 13, 100 the member 11 thereof is provided with a rib 16 which contacts with the upper edge of the plate 3. Near the outer end thereof, the member 12 of the arm 10 is provided with a curtain pole receiving recess 17, and 105 at its outer end this part is provided with a pendant portion 18 the sole function of

which is to give said end an ornamental appearance. A shade roller supporting lug 19 extends forwardly from the outer edge of the member 11 of the arm 10.

- 5 In practice, a shade bracket and curtain pole support is secured to each side 1 of the window or other frame. The prongs 4 of the devices are embedded in the inner and outer edges of the sides 1, and the friction 10 blocks 9 contact with the outer faces of the sides. After adjusting the arms 10 upon the plates 3 to adapt them to the length of the shade roller to be supported, said parts are secured in adjusted position. The shade 15 roller shown in dotted lines and designated 20 is then applied to the lugs 19. After this has been done, the curtain pole shown in dotted lines and designated 21 is mounted in the recesses 17.
- 20 From the foregoing description, taken in connection with the accompanying drawing, the advantages of the construction of the combined window shade bracket and curtain pole support will be readily apparent to 25 those skilled in the art to which it appertains. While I have described and shown what I now consider to be the best embodi-

ment of the invention, I desire to have it understood that such changes may be made when desired as are within the scope of the 30 invention as claimed.

What is claimed is:—

1. A bracket of the character set forth comprising a plate provided at its ends with 35 spring arms carrying prongs and intermediate its ends with a spring tongue carrying a friction block, said prongs and block constituting means adapted to secure the plate to a support and the spring arms and tongue constituting means adapted to hold 40 said prongs and block in engagement with the support, and supporting elements connected to the plate.

2. A bracket of the character set forth comprising a plate, elements carried by the 45 plate for engagement with a support, a spring carried by the plate, a friction block carried by the spring and adapted to be held in contact with the support to assist 50 said elements in securing the plate to the support, and supporting elements carried by the plate.

In testimony whereof I affix my signature.
JOHN J. FISCHER.
